Primary Examiner — Cathron Brooks*Assistant Examiner* — Barbara Fox(74) *Attorney, Agent, or Firm* — Reinhart Boerner Van Deuren s.c.(57) **CLAIM**

The ornamental design for a cheese food product, as shown and described.

DESCRIPTION

FIG. 1 is an isometric view of a cheese food product showing my design from the top and the front side and the left side; FIG. 2 is a top plan view of the cheese food product illustrated in FIG. 1;

FIG. 3 is a front side elevation view of the cheese food product illustrated in FIGS. 1 and 2, the rear side of the cheese food product opposite the front side illustrated in FIG. 3 being a mirror image thereof;

FIG. 4 is a left side elevation view of the cheese food product illustrated in FIGS. 1 through 3, the right side of the cheese food product opposite the left side illustrated in FIG. 4 being a mirror image thereof; and,

FIG. 5 is a bottom plan view of the cheese food product illustrated in FIGS. 1 through 4.
